PRESSURE RELEASE VALVE

Thomas E. Nichols, Houston, Tex., assignor of
one-half to Scott Red, Houston, Tex.

Application July 29, 1941, Serial No. 404,448

5 Claims. (Cl. 158—36.3)

This application is a continuation-in-part of my previously filed application, Serial No. 244,259, filed December 6, 1938, for Pressure release valve.

This invention relates in general to pressure release valve and has for its general object the provision of such a valve which may be employed in connection with the fuel pump and carburetor, or the like, of an internal combustion engine to prevent flooding of the carburetor, or the like, after the engine has been stopped, and to prevent wastage of fuel.

While this invention is applicable to any situation in which there is a fluid supply under pressure which is to be transmitted to a point of use where its flow is controlled by a valve, and it is desired to avoid leakage from the source of fluid under pressure past such valve during periods of idleness immediately following periods of use, this device is especially adapted for use in the fuel system of an internal combustion engine such as is commonly found in an automobile.

In the ordinary fuel supply system used in automobiles, the fuel is fed by means of a pump, or some other suitable apparatus under pressure to the carburetor. Its flow into the carburetor is controlled by a float actuated needle valve. Most such fuel pumps furnish fuel at a pressure of several pounds per square inch more than is actually required to feed the fuel to the carburetor. Upon investigation of many cases of automobiles which were found to be hard to start after having been in operation but a short time before, I have discovered that the apparent reason for such difficult starting is that the fuel under pressure between the pump and the needle valve of the carburetor when the engine is stopped slowly leaks past such needle valve into the carburetor, thereby providing an excessive fuel supply and resulting in what is ordinarily termed "flooding of the engine," which prevents it from being readily started.

It is a more specific object of this invention, therefore, to provide a means whereby such excessive pressure of fuel between the fuel pump and the needle valve of the carburetor may be relieved upon stoppage of the engine and whereby this may be accomplished without the wastage of fuel.

It has also been found that the immediate source of fuel into the carburetor as a result of the starting of the engine and the opening of the needle valve often times causing flooding of the carburetor and causes the engine to stop almost immediately after it has started, and thereafter prevent it from being readily started again.

It is, therefore, another specific object of this invention to provide a device which will prevent the surge of an excessive supply of fuel into the carburetor immediately after the engine has started.

Other objects and advantages of this invention will become apparent from the following description taken in connection with the accompanying drawings in which is illustrated one embodiment of this invention.

In the drawings:

Figure 1 is fragmentary side elevation of a device constructed in accordance with this invention shown in the position it occupies with respect to the fuel pump and carburetor of an internal combustion engine such as is commonly used in an automobile.

Figure 2 shows a longitudinal cross-section through the valve illustrated in Figure 1.

Figure 3 shows a transverse cross-section through the same valve taken along the line 3—3 of Figure 2.

Figure 4 is a view similar to Figure 3, but taken along the line 4—4 of Figure 2.

In Figure 1 there is shown diagrammatically an engine 1 which may be the usual type of internal combustion engine employed in automobiles. The intake manifold of this engine is shown at 2 and the carburetor is shown at 3 for supplying a proper fuel mixture to the manifold. The fuel is intended to be supplied to the carburetor by means of a fuel pump 4, connected in the usual manner for operation by the engine 1, which draws the fuel through a suitable conduit 5 from the fuel tank or reservoir. Within the portion 6 of the carburetor is customarily located a chamber having a float therein which controls the needle valve, closing the valve when the float rises and opening the valve when the float falls. This serves to control the entry of fuel into the carburetor through the opening 7.

The device of this invention is connected to the pump 4 by means of a pipe 8 and to the intake opening 7 of the carburetor by means of another pipe 9. It consists of a main body portion 10 covered by a cover member 11 and having an internal structure such as will be presently described. In addition to the intake port 12 which is connected to the pipe 8 and the outlet port 13, which is connected to pipe 9, the body 10 has relief port 14 which is connected to a pipe 15 and the pipe 15 is in turn connected through a T fitting 16 to the intake for the pump 4.

Referring now more specifically to the internal structure of the device, as illustrated in Figures

2, 3 and 4, the body 10 has integrally formed therewith and substantially coaxially arranged therein, an annular wall 17 forming a cylindrical chamber 18 from the bottom substantially to the top of the member 10 and leaving an annular chamber 19 outside and surrounding the cylinder 18. The intake opening 12 of member 10 communicates directly with the lower end portion of the cylinder 18 so that fuel entering through the port 12 is discharged directly into cylinder 18 at its lower end.

Adjacent its upper end the wall 17 is provided with a plurality of spaced radial openings 20 providing communication between the interior of the cylinder 18 and the annular space 19 surrounding this cylinder. The cover member 11 may or may not close the upper end of the cylinder 18, this being immaterial to the operation of the device. The only essential function of this cover member is to close the upper end of member 10.

The outlet port 13 communicates directly with the annular space or chamber 19 within the member 10 at a point spaced somewhat below the openings 20, but a considerable distance above the lower end of member 10.

The opening 14 which is provided for the relief of pressure, as will be presently described, extends through the annular space 19 to communicate with the interior of the cylinder 18 only at a point intermediate the ends of this cylinder.

Slidably mounted within the cylinder 18 is a piston 21, this piston being hollow for the major portion of its length, but being closed at its upper end as shown at 22. Preferably, this piston is made with relatively thick walls so as to provide it with a substantial amount of weight, the amount of weight provided however being dependent upon the pressure which is ordinarily provided by the pump, it being obvious that the weight of the piston should not be great enough to interfere with the normal operation of the pump. Also, the opening through the piston must, of course, be sufficiently large so that it will be able to allow free passage of sufficient fuel to supply the carburetor under all conditions. The piston is fitted within the cylinder 18 with a relatively close fit, but is not provided with packing to prevent leakage about the piston. For this reason, there may be a small amount of leakage past the piston at all times where there is sufficient differential pressure at two points on the length of the piston to cause leakage.

Adjacent its upper end, the piston is provided with a plurality of spaced radial openings 23 providing communication between the hollow interior of the piston and the exterior of the piston, and these openings are so positioned that when the piston is in its uppermost position within the cylinder 18, these openings will be substantially on the same level as the opening 20 and the openings 23 are made of substantially the same size and number as the openings 20. On its outer surface the piston 21 is provided with a groove 24 extending circumferentially and interconnecting the various openings 23. This is for the purpose of insuring that whenever the piston is in its upper-most position there will be communication between the hollow interior of the piston and the annular space 19 through the openings 20 and 23 and the channel or groove 24.

Intermediate its ends and below the openings 23 the piston is provided with another passage or opening 25 providing communication between its

5 hollow interior and its exterior. There is also a circumferential groove in the exterior surface of the piston as shown at 26 on the same level as the opening 25. This groove and opening are so positioned that when the piston is in its uppermost position they will lie a substantial distance above the relief port 14, but when the piston has moved downwardly a substantial distance and the groove 24 and the openings 20 no longer register, the groove 26 and the relief port 14 will come into register, thus providing communication between the interior of the cylinder 18 and the piston 21, and the relief port 14.

In operation, when the engine to which a device of this kind is connected, is started, the pump will start operating and will cause a build up of pressure below and within the piston 21. This will tend to raise the piston 21 and this piston will move towards the top of the cylinder 18. As above stated, the upper end of the cylinder 18 may or may not be completely closed by the cover 11. If it be assumed that the upper end of the cylinder 18 is closed by the cover 11, then as soon as the upper end of the piston 21 closes the port 20, further upward movement of the piston will be accomplished as leakage takes place from above the piston down around the piston and into the ports 20. In a very few seconds the piston will rise until the ports 20 and 23 register, whereupon fuel will flow through those ports in whatever amounts may be required. During this time before the ports register the engine may operate on the fuel in the carburetor bowl. At all times while the pump is running there is, of course, a minute leakage past the piston into the port 14 and thence back through the by-pass 15 to the pump intake 4. This leakage, however, is so small as to be inconsequential during the operation of the engine.

40 If it be assumed that the upper end of the cylinder 18 is not closed by cover 11, the operation would be the same except that the piston could move completely to the upper end of its travel without necessity for leakage.

45 In the event the engine should stop or be shut off and the needle valve admitting fuel to the engine should for that reason, or any other reason, be closed there will remain within cylinder 18, the piston 21, the chamber 19, and the line 9, a quantity of fuel under pressure. However, when the engine is shut off and stops as it would be if the needle valve were closed for any reason, the pump will also stop.

50 The present invention has for its purpose the provision of a means whereby under those circumstances the pressure existing within the space indicated when the motor stops will be bled off and by-passed back to the fuel supply so that it will not be caused to leak past the needle valve into the carburetor, and cause flooding of the carburetor or wastage of fuel.

55 The device does not operate to relieve the said pressure instantaneously when the motor stops. However, when the motor stops the pressure in the chamber 19 and that within the cylinder 18 being substantially equal, the piston will begin to move downwardly under its own weight as rapidly as leakage can take place from the upper edges of the port 23 upwardly into and through port 20. This leakage in itself, will 60 of course, not relieve the pressure either within the cylinder 18 or the chamber 19, but there may be some leakage past the piston into the port 14 which will somewhat relieve the pressure within these spaces during this time. As soon as the

piston has dropped far enough to enable the groove 26 to begin to register with the port 14, any pressure remaining within the cylinder 18 and within the chamber 19 will be immediately relieved as a substantial quantity of the fluid flows out through port 14 and as the piston 23 drops in consequence of such flow. This relieves the pressure on the needle valve of the carburetor so that as the motor stands idle there will not be a leakage past this needle valve to flood the carburetor or to waste fuel. Instead, the pressure is relieved by bleeding the fuel back to the fuel supply and when it is again desired to start the motor, it will be found to be in perfect condition for starting with no flooded condition existing.

When the motor is again started, there will be a relatively small amount of fuel remaining within the carburetor bowl so that the motor may run until the piston 21 is forced upwardly to the point where the ports 20 and 23 come into communication with each other. The fuel in the chamber 19 below the ports 20 may be forced by the pressure of the rising piston to flow slowly into the carburetor during this period, but there cannot be an excessive surge of fuel into the carburetor, such as would cause flooding thereof.

In view of the foregoing, it will be appreciated that a means has been provided for carrying out all of the objects and advantages sought by this invention.

Having described my invention, I claim:

1. In a device of the character described, a carburetor having a float operated needle valve therein for controlling the flow of fuel into said carburetor, a pump for supplying fuel under pressure to said carburetor, a body having a valve chamber therein connected at one point to the outlet of said pump to receive fuel under pressure therefrom and at another point to the needle valve of said carburetor to supply fuel under pressure thereto, said chamber having a pressure relief port therein connected to the intake of said pump for relieving excessive pressure of fuel between said pump and said carburetor needle valve when said valve closes, and means in said chamber in the path of fluid under pressure flowing through said chamber from said pump to said needle valve and freely movable thereby toward the connection with said needle valve to a position covering said relief port to maintain said relief port closed, and said means being freely retractable away from the connection with said needle valve when no fluid is flowing through said chamber to open said relief port and relieve pressure of fluid throughout said chamber and on said needle valve.

2. A pressure release valve comprising a casing having a fluid outlet chamber adapted to be connected to a device utilizing fluid under pressure, said casing having an inlet fluid chamber adapted to be connected to a fluid pressure pump, said casing having ports to communicate said chambers, a piston type valve operating in the inlet fluid chamber between the inlet of the inlet fluid chamber and said communicating ports and movable toward said ports under the fluid pressure from the pump and having a groove having ports to register with the ports of the casing to open and close the chambers to each other in accordance with the balancing and unbalancing of fluid pressures within said chambers, and a by-pass means connected to the receiving side of the pump and to the inlet fluid chamber and being opened to the latter-named chamber by said

valve when said valve moves away from said communicating ports.

3. In combination with a fluid fuel pressure pump and the carburetor of an engine, a pressure release valve comprising a casing having a fluid outlet chamber adapted to be connected to a float chamber of the carburetor, said casing having an inlet fluid chamber adapted to be connected to the fluid fuel pressure pump, said casing having ports to communicate said inlet and outlet chambers, a piston-type valve movable in the direction of fluid flow in the inlet fluid chamber under fluid pressure from the pump and having an outside annular groove therein having ports to register with the ports of the casing to open the chambers to each other upon such movement, a by-pass pipe connected to the fluid receiving side of the pump, said casing having a passage from said inlet chamber with the by-pass pipe connected thereto, said piston type valve having a part substantially closing said passage when said valve is in a position to open said inlet and outlet chambers to each other, and having a port movable to register with and open said passage upon cessation of fluid flow into said inlet chamber to permit by-passing of fluid from the fluid inlet chamber back to the receiving side of the pump.

4. In combination with a pressure fuel supply and the carburetor of an engine, a pressure release valve for fuel systems of internal combustion engines comprising a vertically arranged cylinder having an intake port in the lower end thereof and adapted for connection to the pressure fuel supply, a chamber arranged about said cylinder and having a port adjacent the upper end thereof and adapted for connection to the carburetor, said cylinder having ports adjacent the upper end thereof to communicate the cylinder with said chamber, a bypass means connected to said cylinder below the ports of said cylinder and adapted to be connected to the fuel supply, and a gravity influenced, piston-type valve slidable in the cylinder and movable in the direction of flow by the differential between the pressure of the fuel supply and the pressure of fuel in said chamber to open the ports of said cylinder and to close the bypass means so as to permit fuel to flow to the carburetor, and movable by gravity to automatically close the ports of said cylinder and open said bypass means when the flow of fuel to the carburetor is stopped by the closing of a fuel float chamber thereof causing a back pressure of fuel in said fuel chamber which equals the pressure of fuel from the fuel supply.

5. A pressure release valve for fuel system of internal combustion engines comprising a vertically arranged cylinder having a fuel inlet port in the lower end thereof adapted for connection to a pressure fuel source, a chamber formed on said cylinder and surrounding the vertical walls of the cylinder and having a port adapted for connection to a carburetor of an engine, said cylinder having ports adjacent the upper end thereof to connect the chamber therewith, said cylinder having a bypass passage located substantially intermediate the ends thereof and extending through the chamber with non-communication therewith and adapted to be connected to the fuel source for the return of fuel thereto, and a piston slidable in said cylinder between said fuel inlet port and the ports adjacent the upper end of the cylinder and said piston being influenced by gravity, and hav-

ing ports adjacent the upper end thereof, and said piston being movable under differential of pressure between said cylinder and said chamber to align the ports of the piston with the ports adjacent the upper end of the cylinder when there is a flow of fuel from the source of the carburetor and said piston being adapted to be moved by gravity to move the ports of the piston out of alignment with the ports of

said cylinder by the gravitation of the piston thereby bringing about closing of said cylinder to the chamber when the flow of fuel into said carburetor is stopped, said piston having a port to align with the bypass passage when said piston lowers to close the ports of said cylinder and thereby permit return of the fuel to the source from the cylinder.

THOMAS E. NICHOLS.
